JEWEL

William F. Schmalz, Rockville, Conn., assignor to
Colt's Patent Fire Arms Manufacturing Company, Hartford, Conn., a corporation of Connecticut

Application July 8, 1940, Serial No. 344,302

3 Claims. (Cl. 63—32)

The invention relates to jewels, and more particularly to jewels of the flat-backed type formed from light transmitting material; the term "flat-backed" is used herein to mean a substantially plane back, although a limited degree of convexity or concavity is contemplated.

The primary object of the invention is to provide a flat-backed jewel of novel construction such that the jewel has a brilliance greater than that characteristic of the light transmitting material from which it is formed, the construction being such that the jewel is relatively inexpensive to manufacture.

Another object is to provide a jewel of the above character and which is hollow, the inner and outer surfaces of which have their opposing portions extending nonparallelly to impart "life" to the jewel.

Further objects and advantages of the invention will be apparent from this specification to those skilled in the art.

In the accompanying drawing I have shown the now preferred embodiments of the invention, but it will be understood that the drawing is intended for illustrative purposes only and is not to be construed as defining or limiting the scope of the invention, the claims forming a part of this specification being relied upon for that purpose.

In the drawing:

Figs. 1 and 2 are, respectively, plan and sectional elevational views of a jewel incorporating the principles of one phase of the invention.

Fig. 3 is an enlarged fragmentary sectional view taken on the line 3—3 of Fig. 1.

Fig. 4 is a bottom plan view of the jewel shown in Figs. 1-3.

Figs. 5 and 6 are, respectively, plan and sectional elevational views of a jewel incorporating the principles of another phase of the invention.

Figs. 7 and 8 are, respectively, plan and sectional elevational views of a jewel incorporating certain further principles of the invention.

A flat-backed jewel is ordinarily lacking in brilliance due to the fact that from the very nature of its shape there is little internal reflection of light rays entering the face of the jewel, and this is particularly true of jewels used for costume jewelry and similar purposes made in imitation of precious or semiprecious jewels. In accordance with the broader aspects of one phase of the invention, a flat-backed jewel construction is provided in which means having a reflecting surface is secured to the back of the jewel to increase its brilliance. The reflecting means is preferably a relatively stiff polished metallic disc

formed either solely of metal of sufficient thickness to have the desired stiffness or of a thin sheet of metal stiffened by a backing material such as cardboard, for example. More specific aspects of this phase of the invention include the recessing of the back of the jewel, such as by providing a relatively thin rearwardly extending peripheral flange, and securing the reflecting metallic disc within such recess.

For the purposes of this specification the principles of the invention have been illustrated as they may be applied to a jewel of "rose cut," but it will be obvious that they are equally applicable to any flat-backed jewel.

Referring to the drawing, and more particularly to Figs. 1, 2, 3 and 4, there is shown a "rose cut" jewel having a body 1 formed of light transmitting material. Any desired and suitable light transmitting material may be used, although it is now preferred to use one from which the shaped body of the jewel may be inexpensively manufactured. Among the suitable materials are the synthetic resins polystyrene and methyl methacrylate, cellulose acetate, and glass, but for reasons which will become apparent hereinafter it is preferable to use a material, such as one of the first three named, which is relatively soft and which may be plasticized at a relatively low temperature. When formed of any of the foregoing materials, the body is shaped by any of the well-known methods of molding these materials. The body 1 is recessed at its back, an integral flange 2 serving to form the recess. A reflecting disc 3 is secured within the recess and serves to reflect the light rays entering the face of the jewel. The illustrated disc is made wholly of metal, being preferably formed by stamping it from a sheet or strip of polished nickel or chromium plated stock having a thickness of about .008". It is preferred to make the flange 2 as thin as is feasible so that the disc may be substantially coextensive in area with the back of the body to thus reduce to a minimum the area of lesser brilliance. While the disc may be secured within the recess in any desired manner, a forced fit with the flange 2 frictionally engaging the peripheral edge of the disc will in most instances hold the body and disc in proper relative positions and assembled relationship. When the body is formed of a relatively soft and easily plasticized material, any burrs or slight roughness at the edge of the disc resulting from the stamping operation cut into the material of the flange 2 to more firmly secure the disc within the recesses, and some of the material of the

flange, or small projections molded integrally therewith, may be softened with a heated tool and flowed radially inward over the back of the disc to form lugs 4 which aid in securing the disc within the recess as shown in Figs. 3 and 4.

Brilliance and "life" are, of course, desirable in jewels and their attainment is to a large extent dependent upon the faceting of the jewel, the greater the number of facets, the more brilliance and "life" a jewel of any particular basic shape and material will have. However, as the number of facets is increased the angle of intersection of adjacent facets also increases, and when the jewel is made by a molding process it becomes more difficult to maintain a sharp line of facet intersection as the angle of intersection increases. In accordance with another phase of the invention, provision is made for increasing the "life" of a flat-backed jewel without increasing the angle of intersection of the facets. This is accomplished by providing a relatively deep recess in the back of the body of the jewel such that opposed portions of the inner and outer surfaces of the body extend nonparallelly; and more specifically, it is preferable that, in addition to the foregoing relationship, at least one of the surfaces be faceted or that both be faceted. A jewel incorporating these principles has more "life" due to the effect the nonparallel relationship of the opposed portions of the inner and outer surface of the body has on the light rays reflected from the back of the jewel.

In Figs. 5 and 6 is shown a jewel having a body 5 with a faceted exterior surface and preferably made by molding from one of the light transmitting materials above-mentioned. A relatively deep recess 6 is formed in the back of the body to provide an inner surface in the body which is so shaped and related to the outer faceted surface that opposed portions of the two surfaces extend nonparallelly. A metallic reflecting disc 7, similar to that shown in Figs. 1-4, is secured to the back of the jewel by frictional engagement with flange 8 and lugs 9. In constructions incorporating the principles of this phase of the invention it is particularly important that the light rays entering the face of the jewel be reflected as it is the passage of these reflected rays through the nonparallelly extending surfaces which imparts "life" to the jewel.

While a substantially conical recess is shown in Figs. 5 and 6 it should be understood that other shapes may be used and that the appearance of the jewel will be controlled by the shapes of the inner and outer surfaces. Figs. 7 and 8 illustrate a jewel having a combination of surface shapes which is particularly effective. The jewel comprises a body 10 of light transmitting material which is exteriorly faceted as indicated by

the solid lines in Fig. 7. The back of the body is deeply recessed at 11 and the inner surface is faceted as indicated by the dash lines in Fig. 7. The interior faceting is similar to the exterior, but, as is apparent from the figures, the interior facets are offset relative to the exterior ones with the result that opposed portions of the inner and outer surfaces of the body extend nonparallelly. A metallic reflecting disc 12 is suitably secured to the back of the jewel by flange 13 and lugs 14. The illustrated shape and relationship of surfaces greatly increases, in effect, the number of facets without increasing the angles of intersection of the facets to thereby permit the maintenance of sharp lines of intersection of the facets.

Various changes and modifications within the scope of the invention will be apparent to those skilled in the art.

What I claim is:

- 20 1. A flat-backed jewel comprising in combination, a shaped body of light transmitting material having an outer surface composed of a plurality of facets formed at the edges thereof and also having a relatively deep recess in the back of said body to provide an inner surface therefor, said inner surface being composed of a plurality of substantially flat surface portions of which the majority thereof extend generally nonparallelly in opposed relationship to the majority of the facets of said outer surface, and a member secured to the back of said body and having a reflecting surface spaced from said inner surface of said body.
- 25 2. A flat-backed jewel comprising in combination, a shaped body of light transmitting material having an outer surface composed of a plurality of adjoining surface portions and also having a relatively deep recess in the back of said body to provide an inner surface therefor comprising a plurality of facets joined at their abutting edges, said facets and adjoining surface portions of said outer surface being respectively misaligned with each other, and a member secured to said back of said body and having a reflecting surface spaced from said inner surface of said body.
- 30 3. A flat-backed jewel comprising in combination, a shaped body of light transmitting material having an outer surface and a relatively deep recess in the back of said body to provide an inner surface therefor, said inner and outer surfaces each being provided with a plurality of facets joined at their abutting edges and substantially all of said facets of said inner and outer surfaces being respectively non-parallel to each other, and a member secured to said back of said body and having a reflecting surface spaced from said inner surface of said body.

WILLIAM F. SCHMALZ.
